Fig. 21.

Fig. 22

This technical drawing illustrates a mechanical assembly, likely a cylinder or piston rod, with various dimensions and part numbers. The assembly is shown in three views: a front view on the left, a top view in the center, and a side view on the right. The front view shows a total height of 248 and a width of 243. The top view shows a total width of 250 and a central hole with a diameter of d . The side view shows a total height of 249 and a width of 245. Key dimensions include: front view height 248, front view width 243, top view width 250, top view hole diameter d , side view height 249, side view width 245, top view central hole diameter d , top view side width 254, top view side height 253, side view side width 254, side view side height 253, side view side width 255, side view side height 256, top view side width 257, top view side height 258, side view side width 257, side view side height 258, and side view side width 249. Part numbers 243, 245, 246, 247, 248, 249, 250, 251, 252, 253, 254, 255, 256, 257, 258, and 249 are also present.

A technical drawing of a rectangular frame. On the right side, there are four dimensions labeled vertically: 257, 256, 254, and 255. On the far right, there is a dimension 249. The frame has three circular holes on the left side, each with a dimension of 256. The top and bottom edges of the frame have a dimension of 257. The right edge has a dimension of 254. The left edge has a dimension of 255. The bottom edge of the frame has a dimension of 249.

TWIN DIAPHRAGM PUMP WITH STRESS-RELIEVED DIAPHRAGMS

Frank L. Graner, Cold Spring, N. Y., assignor to
 The Dorr Company, Stamford, Conn., a corporation of Delaware

Application June 19, 1952, Serial No. 294,393

10 Claims. (Cl. 103—152)

1

This invention relates to diaphragm type pumps suited for pumping abrasive slurries, chemical solutions, acids or other corrosive liquids, solids-carrying liquids, viscous pulps, or high density liquids or sludges derived, for example, from mechanical thickeners, gravity settlers or the like. However, the material being handled by these diaphragm pumps will herein be briefly referred to merely as slurry. Such a pump comprises as part of a pump chamber a deformable disc-shaped diaphragm member and actuating means for reciprocatively bulging the diaphragm inwardly and outwardly in alternation thereby drawing the liquid through an inlet check valve into the pump chamber during the suction stroke, and displacing or expelling liquid through an outlet check valve from the chamber during the delivery stroke of the pump.

Stroke adjusting devices are often provided in conjunction with the actuating means for varying the rate of delivery of the pump by varying the pump stroke even while the pump is running.

More in particular, this invention relates to diaphragm type pumps having stress-relieved diaphragms, and which will herein be termed stress-relieved diaphragm pumps. Such a pump may deliver against a desired pressure without having the diaphragm itself subjected to the stress resulting from such pressure. In such a pump the stress-relief for the diaphragm is due to diaphragm-actuating means which employ a pressure-transmitting fluid medium or operating liquid to act upon the diaphragm for reciprocating the same. That is to say, the pressure of the operating fluid contacting the outside of the diaphragm balances the pressure of the fluid or slurry contacting the opposite or inner side of the diaphragm so that the diaphragm being confined between liquids from both sides is substantially completely stress-relieved while pumping.

The general purpose and character of stress-relieved diaphragm pumps will be more fully understood by their comparison with the more ordinary non-relieved type of diaphragm pump in which the diaphragm is actuated by a reciprocating rod attached directly to the diaphragm which is thus subject to the full pumping pressure and therefore to mechanical stresses and to a degree of stretching commensurate with such pressure. The non-relieved diaphragm pump is therefore not normally qualified to deliver against any appreciable pressure except at the price of correspondingly increased mechanical stresses and stretching and wear imposed upon the diaphragm with a corresponding concurrent reduction in

2

volumetric pumping efficiency. Therefore, such a pump is not well qualified to answer a requirement of furnishing what may be termed a metered discharge as visualized by this invention especially within wide limits of stroke adjustment and delivery rates, for example, between limits of zero and maximum. The requisites of a truly metered discharge as visualized by this invention are that the delivery rate adjusted to a value within such wide limits as zero and maximum should remain constant irrespective of variations in the discharge pressure or resistance or head against which the pump must operate.

By contrast, the stress-relieved diaphragm pump is capable of delivering against relatively high pressures, higher indeed than any pressures normally attainable by the non-relieved diaphragm pump, yet without impairment of volumetric pumping efficiency, and it is adjustable as to delivery rates within a wide range (as between zero and maximum) substantially without loss of volumetric efficiency.

In a stress-relieved diaphragm pump of known construction the operating liquid was confined in a hydraulic operating chamber surrounding the outside of the diaphragm, and having associated therewith a reciprocating piston or plunger to act upon this confined volume of operating liquid in a manner to impart alternatingly suction and pressure to the diaphragm. In this way the diaphragm was reciprocated through the intermediary of the operating liquid to effect pumping of the slurry. Consequently, adjustable control devices for varying the delivery rate of such a pump have been provided in direct association with the piston-actuating means for varying the piston stroke. Yet, while a variety of stroke adjusting devices either have been or could be employed with diaphragm pumps, their embodiment in a stress-relieved diaphragm pump unit carries with it certain disadvantages in the way of bulkiness and indeed in the way of certain structural as well as operational complications and design limitations especially when such a device is to permit adjusting of the piston stroke and of the delivery rate while the pump is running. For example, the stress-relieved diaphragm pump just outlined is equipped with stroke-adjusting devices for the piston or plunger capable of being manipulated only when the pump is stopped. Thus, a problem lies in providing a metering type diaphragm pump which is independent of and does not require any of the conventional stroke-adjusting devices, and whereby the inconvenience of stopping the pump is avoided in that adjust-

ment can be effected while the pump is running.

Also in the above outlined stress-relieved diaphragm pump, since the volume of the pressure transmitting operating liquid is confined in a hydraulic operating chamber about the outer side of the diaphragm, it requires certain accessories in the nature of pressure relief devices as well as devices automatically supplying make-up operating liquid to the operating chamber, which devices represent structural as well as operational complications in the pump. The relief devices are employed to meet the emergency or the possibility of a clogged discharge pipe, whereas the make-up device should function to replace operating liquid which may be lost from the chamber through the relief device or otherwise. Thus, another problem lies in avoiding the need of employing such relief and make-up devices.

Still another drawback in the above outlined stress-relieved diaphragm pump lies in that they require expensive and bulky motor driven reduction gearing for actuating the piston or plunger of the hydraulic operating chamber. Hence, it is another problem to provide a stress-relieved diaphragm pump unit without the need for such gearing.

Therefore, it is among the objects of this invention to provide a stress-relieved diaphragm pump unit which meets the metering requisites above set forth in that it has a uniformly high volumetric efficiency over a wide range of delivery rates as between zero and maximum and maintains the adjusted delivery rate substantially constant in spite of variations of or fluctuations in the delivery pressure; which is relatively simple and compact even though capable of relatively high maximum delivery rates; which is accurately and sensitively controllable in a simple and convenient manner as to the adjustment of the metered discharge rate even while the pump is running; which is immune to the effects of possible clogging or obstruction of the discharge pipe without involving the use of the conventional relief and make-up devices above referred to; and which provides diaphragm actuating means requiring none of the conventional gearing above referred to.

A known construction of a stress-relieved type of diaphragm pump provides for such a pump that is double acting in that a single actuating plunger or piston reciprocating between a pair of hydraulic operating chambers and diaphragms exerts during one stroke hydraulic pressure upon the diaphragm of one chamber while by the same token applying suction to an opposite diaphragm, and vice versa, during the succeeding stroke. Since such a pump requires and is provided with the aforementioned pressure-relief devices and water make-up devices, as well as with a prime mover or motor and gearing for reciprocating the actuating piston, it is another object to provide an improved double-acting pump free from such drawbacks.

These objects are attained in a double-acting pump unit in which the two diaphragms in a pump housing are mechanically and kinematically so interconnected as to move in unison, and they are furthermore operationally connected with a spool type control valve means whereby hydraulic operating water from a pressure water supply is admitted to one of the hydraulic actuating chambers while operating water is being released from the opposite operating chamber, and vice versa, as the valve means operate through a pumping cycle. In fact, the control

valve means according to this invention comprises a primary or spool valve member and a secondary or slideable sleeve valve member within which the spool operates, the sleeve member being provided with an arrangement of port openings bearing certain cooperative relationships with respect to the spool. The spool and the sleeve are movable axially relative to one another, the sleeve in turn being movable axially in a valve housing which is fixedly associated with the pump housing. The sleeve or secondary valve member is kinematically connected with both diaphragms so as to move in unison therewith, whereas the spool or primary valve member is controllably reciprocatable by a suitable drive.

The controlled movement of the spool within the sleeve member admits operating water under pressure to one of the hydraulic operating chambers while releasing such water from the other chamber, and vice versa, through a pumping cycle, thereby reciprocating the diaphragms.

In other words, the valve-controlled operation of the pump is initiated and maintained by the movement of the spool relative to the sleeve, which through control of operating water actuates the diaphragms which in turn move the valve sleeve member in unison therewith. The net result is that the movements of the sleeve and of the diaphragms in unison substantially follow and reflect the controlling movement of the spool so that varying the stroke of the valve spool member will correspondingly affect or influence the movement of the diaphragms and the pumping rate.

In fact, this "follow-up" relationship between the sleeve member and the spool member enables the pump to adjust itself automatically to variations of discharge head or back pressure at the discharge end of the pump in a manner whereby the pump will automatically maintain a predetermined and adjusted rate of metered discharge. Indeed, with every change, namely increase or decrease in the magnitude of the discharge head or back pressure this control valve will respond in a compensatory fashion by proportionately decreasing or increasing the throttling effect or pressure drop of the pressure water being admitted through the control valve to the respective hydraulic operating chambers. That is to say, whenever the back pressure at the discharge end of the pump increases, it will momentarily retard the movement of the diaphragm and thereby equally retard the movement of the sleeve member with which it is kinematically coupled. Thus, since the spool member continues at its adjusted rate of speed and reciprocatory frequency, there will occur a corresponding slippage between the sleeve member and the spool member, the amount of that slippage being sufficient to increase the effective through-flow area of the port openings in the sleeve member until there is attained a decrease in pressure drop across the through-flow passages or port openings, substantially proportionate to the aforementioned increase in back pressure at the discharge end of the pump. Hence, as a result of such load induced slippage between the telescoping moving parts of the control valve there is admitted to the respective hydraulic operating chambers a relatively increased water pressure sufficient to balance the increased pumping pressure. Correspondingly, with a decrease of back pressure at the discharge end of the pump, the resultant slippage of the sleeve member rela-

tive to the spool member is in the opposite direction, whereby the effective area of the valve through-flow passages or port openings is decreased, so that the pressure admitted to the hydraulic operating chambers is reduced by an amount corresponding to the reduction of back pressure encountered at the delivery end of the pump, so that again the hydraulic operating pressure is in balance with the pumping pressure. In this way the pump automatically absorbs any fluctuations in discharge back pressure substantially without effecting the adjusted rate of metered discharge.

More particularly, to attain the aforementioned objects a double-acting pump according to this invention comprises two pumping sections side by side constituting a common substantially cylindrical housing. Each pumping section or half of this common housing comprises a hydraulic operating chamber at one side of one diaphragm, and a slurry pumping chamber proper at the other side of that diaphragm. Thus, the two hydraulic operating chambers may constitute the outer ends of the common housing, while the two pumping chambers constitute the intermediate portion of this common housing; each hydraulic operating chamber has a port or connection with the spool type control valve means, allowing hydraulic operating water to enter as well as leave the operating chamber in the course of a pumping cycle of that pumping section, whereas each pumping chamber has a suitable check valve for slurry inlet as well as a check valve for slurry outlet. The diaphragms reciprocate in unison due to a link construction operatively interconnecting them. The spool type control valve means comprises a cylindrical housing having a supply connection for pressure water to be controllably admitted through the valve means to respective operative chambers in alternation, and a spent water discharge connection for such operating water to be controllably released and displaced from respective hydraulic operating chambers through the valve means incident to the operation of the spool member and the sleeve member relative to one another and relative to the valve housing.

According to one feature, pressure water for the hydraulic operating chambers is supplied through the valve means by a centrifugal servo-pump while spent water from the operating chamber passing through the valve means returns to the suction side of the pump, so that the diaphragm pump proper together with the servo-pump and various passages leading to, through, and from the control valve means between the pumps constitute a closed circulating system for the operating water. Moreover, the suction end of the servo-pump communicates with an expansion chamber or reservoir which supplies the need for or absorbs the excess of operating water, thus dispensing with the aforementioned relief devices and make-up devices. In case the discharge of the diaphragm pump should get clogged or blocked, relief is automatically provided with the centrifugal pump merely continuing to run against what is the normal maximum pressure producible by the pump.

According to another feature, the controlling reciprocating motion of the valve spool member is imparted thereto by means of a motorized servo-drive unit embodying stroke adjustment means. Further particularized, a servo-drive

unit herein proposed lends itself to effecting the stroke adjustment by remote control.

Other features lie in the manner in which the diaphragms are operatively interconnected for movement in unison, as well as kinematically connected to the valve sleeve member, whereby the diaphragms move in unison with the sleeve member. According to one such feature, each diaphragm has a stem pointing outwardly to and passing through a respective end of the pump housing and in sealed relationship thereto. The end of each such diaphragm stem has pivotal connection with the end of a swingable arm fixed upon a rocker shaft that is horizontal and extends transversely of the longitudinal horizontal axis of and through the pump housing with one end of the rocker shaft extending outwardly exposed from the housing and in sealed relationship therewith; the exposed ends of both rocker shafts are operatively interconnected by motion transmitting means so that thereby both diaphragms must move simultaneously. Furthermore, the exposed end of one of the rocker shafts has motion transmitting means operatively or kinematically connecting it with the valve sleeve member so that the diaphragms will move in unison therewith.

According to a more specific structural feature, this pump comprises a substantially cylindrical pump housing with a horizontally extending longitudinal axis and having a removable closure plate at each end. The controlling spool valve unit is mounted upon and carried by the pump housing although somewhat at one side thereof and with its longitudinal horizontal axis parallel to that of the pump housing. The two rocker shafts are mounted in a top portion of the pump housing to extend horizontally and transversely of the horizontal longitudinal axis of the pump housing and so that the exposed ends of these two rocker shafts are disposed adjacent to respective ends of the spool valve unit. The motion transmitting means between the exposed ends of these two rocker shafts comprise an actuator arm extending from each exposed end and fixed thereto, both actuator arms being downwardly coextensive and being interconnected at their lower ends by a horizontally extending link member. One of these downward actuator arms has what is in effect an upward extension or upward actuator arm for operatively engaging the valve sleeve member; that is, the sleeve member has a stem portion extending horizontally and axially through one end of the valve housing in water-sealed relationship therewith, the sleeve stem portion having operative connection with the upward actuator arm, so that the sleeve member will move in unison with the diaphragms. The valve spool member has a stem portion extending horizontally and axially through the opposite end of the valve housing in water-sealed relationship therewith, which spool stem portion has operative connection with the aforementioned servo drive unit which in turn is mounted upon and supported by the pump housing.

Other features lie in the structural organization and mutual structural relationship of the main component portions of this pump unit in the special construction of casting representing some such component portions, and in the manner in which these castings are structurally associated with one another.

Still other features reside in the particular construction of the spool type control valve unit. One such feature lies in the fact that the valve

automatically presents additional flow passage or port area for the discharge therethrough of spent water from the operating chambers; in this way the back pressure or flow resistance to the discharge of spent water is minimized. Another feature lies in having the spool valve member so shaped as to accentuate the differential of comparative flow resistance across the pressure port area and the discharge port area.

In summary, this invention provides a double acting stress-relieved diaphragm pump unit in which pressure water is supplied to the hydraulic operating chamber by a centrifugal servo-pump with spent operating water returning to the suction end or low pressure side of the pump. Control valve means in the nature of a spool valve unit are functionally interposed between the servo-pump and the diaphragm pump proper, whereby pressure water is supplied at a controlled rate to the one diaphragm while spent water is released from the other diaphragm, and vice versa, in the course of a pumping cycle. The control valve unit comprises a spool valve member slidable in a sleeve member and both the spool and the sleeve being slidable in and relative to a valve housing. Each of the operating chambers has a two-way passage connecting it with the valve housing while the servo-pump has a pressure and a suction connection with the valve housing, all so disposed that the operation of the valve unit will effect the above mentioned pumping cycle of this double acting diaphragm pump. The valve unit operates to that effect by reason of the diaphragms being operatively linked to each other as well as to the sleeve member so that they all move in unison, while servo-drive means impart to the spool member reciprocations of an adjusted or adjustable length of stroke of an adjustable speed. An expansion chamber or reservoir is provided to communicate with the suction side of the servo-pump.

In the drawings, Figure 1 is a highly diagrammatic sectional view of the stress-relieved diaphragm pump unit showing operating conditions during the stroke in one direction of the pumping cycle.

Figure 2 is a diagrammatic view similar to Figure 1, showing conditions during the opposite stroke of the pumping cycle.

Figure 3 is a less diagrammatic view of the pump unit somewhat more explicit with respect to control mechanism and linkage, but otherwise corresponding to operating conditions shown in the Figure 1.

Figure 4 is a diagrammatic view of the pump unit similar to that of Figure 3, but corresponding to the operating condition shown in Figure 2.

Figure 5 is a perspective view of the pump unit structurally more fully developed with the diaphragm pump itself shown in part section and with part of the unit drawn apart.

Figures 6 to 9 show various views of the pump unit structurally more fully executed than the unit shown in Figure 5; that is, Figure 6 is a top view of the pump unit including a motorized servo-pump and a motorized drive unit for the control valve; Figure 7 is a side view of the pump unit taken on line 7-7 of Figure 6; Figure 8 is a part sectional end view of the pump taken on line 8-8 of Figure 6; Figure 9 is a vertical sectional view of the pump taken on line 9-9 of Figure 8.

Figure 10 is a detail section taken on line 10-10 75

of Figure 8 to show a view upon the discharge end of the diaphragm pump proper.

Figure 11 is a detail sectional view taken on line 11-11 of Figure 8, to show a view upon the flanged top of the housing of the diaphragm pump.

Figure 12 is a detail sectional view taken on line 12-12 in Figure 8, to show a horizontal section of the control valve housing.

Figures 13 and 14 are enlarged perspective views of the telescopically moving parts of the spool type control valve; Figure 13 showing the spool valve member; Figure 14 showing the sleeve valve member.

Figure 14a shows a developed internal view of the valve housing.

Figure 15 is a perspective view of the valve housing with a view taken approximately in the direction indicated by arrow Q in Figure 6, and 20 part sectioned vertically as well as horizontally and also transversely halved with the halves drawn apart.

Figure 16 is a section taken on lines 16-16 of Figure 6.

Figure 17 is a section taken on line 17-17 of Figure 16 or of Figure 12, or of Figure 6.

Figure 18 is a section taken on line 18-18 of Figure 16 or of Figure 12, or of Figure 6.

Figures 19 and 20 are simplified diagrammatic representations of the characteristic operating conditions of the control valve in terms of operating positions of the ports of the slide sleeve member relative to the connections leading to and from the fixed valve housing, with the ports developed in a manner similar to that of Figure 14a.

Figures 21 and 22 are valve operating views corresponding to those of Figures 19 and 20 although indicating structural evolution such as embodied and shown in the valve housing of Figures 15, 16, 17 and 18.

Figures 23 and 24 are enlargements of the longitudinal sectional view of the spool valve shown in Figure 9, although showing more clearly the details of the spool member of Figure 13 and of the sleeve member of Figure 14 as well as their dimensional relationship with Figure 23 corresponding to the operating condition of Figure 1 and Figure 24 corresponding to the operating condition of Figure 2.

50 The basic component portions of sections of the pump unit as viewed in terms of the diagrammatic Figs. 1 and 2 are represented by a diaphragm pump section P proper, a control valve section V, a servo-drive section D, and a pressure water supply section S, all of these component sections B, V, D, S, being defined more clearly with respect to one another by respective dot-and-dash outlines or boxes surrounding them.

55 The pump section P comprises a double-acting diaphragm pump having a housing 16 which has a horizontally extending body portion 11 and end portions 12 and 13, and which housing is subdivided by a transverse central partition wall 10a defining a pair of housing sections 14 and 15. Each of these sections 14 and 15 in turn is subdivided by a pump diaphragm into a pump chamber proper and a hydraulic operating chamber. That is to say, the housing section 14 is divided by a diaphragm 16 into a pumping chamber 17 disposed at the inner side of the diaphragm and a hydraulic operating chamber 18 disposed at the outer side of this diaphragm; similarly, the housing section 15 is divided by a diaphragm 19 into a pumping chamber 20 disposed at the inner

side of the diaphragm and a hydraulic operating chamber 21 disposed at the outer side of the diaphragm. A two-way passage 22 connects the hydraulic operating chamber 18 with the left-hand portion of the housing 37 of control valve section V, while another two-way passage 23 connects the hydraulic operating chamber 21 with the right-hand portion of the housing 37 of control valve section V. The pumping chamber 17 is connected by a two-way passage 24 with a valve head 25 comprising an inlet ball check valve 26 and an outlet ball check valve 27; similarly, the pumping chamber 20 is connected by a two-way passage 28 to a valve head 29 comprising an inlet check valve 30 and an outlet check valve 31.

The diaphragm 16 has a stem 32 extending horizontally and outwardly from it while the diaphragm 19 has a similar stem 33 extending in the opposite direction. For diagrammatic purposes both stems 32 and 33 are shown to extend as through each end of the pump housing 18 and in water-sealed relationship therewith so that the outer ends 34 and 35 of respective diaphragm stems can be operatively interconnected as by an interconnecting member or rod 36 whereby both stems 32 and 33 and their diaphragms 16 and 19 are adapted to move in unison.

The control valve unit V according to diagrammatic Figures 1 and 2 comprises a valve housing 37 horizontally coextensive with the pump housing 18 and having horizontal body portion 38 and end portions 39 and 40. This valve unit V is of the spool and sleeve type comprising a sleeve member 41 having sliding fit in the valve housing and being horizontally slidably movable therein and a spool member 42 having sliding fit within the sleeve member and being horizontally slidably movable therein. The slideable spool member 42, the slideable sleeve member 41, and the fixed valve housing 37 are all horizontally coaxial and their common horizontal axis is parallel to that of the pump housing 18. The joint movement of the diaphragm 16 and 19 is kinematically coupled with the movement of the sleeve member 41 in that there is provided a double-armed vertical lever 43 having its fulcrum point at 44 fixed with respect to the pump housing 18 and as well as with respect to the valve housing 37. The lever 43 has an upwardly extending arm 43^a to connect operatively with the end 35 of diaphragm stem 33, and it has a downwardly extending arm 43^b of lever 43 connecting operatively with the sleeve member 41 in that this sleeve member has a stem portion 45 extending through the end portion 40 of the valve housing in water-sealed relationship therewith. Thus, as the diaphragms 16 and 19 reciprocate, the sleeve member 41 will reciprocate in unison therewith although in relatively opposite directions. The spool member 42 is to be reciprocated independently by means of the servo-drive mechanism D which connects operatively with a stem portion 46 of spool member 42 and extends through the end portion 39 of the valve housing and has water-sealed relationship therewith. It is thus that the diaphragms 16 and 19 will substantially follow and reflect the primary or pilot or leading movements of the reciprocating spool member 42 in a manner more fully described further below.

However, there will now first be given a more detailed description of the parts of the valve unit itself, namely of the interior of the valve housing 37 with respect to certain recesses or chambers therein, of the sleeve member 41 with respect to

70
75

certain port openings therein, and of the spool member 42 with respect to certain flow controlling and flow directing portions thereof. The interior of the valve housing 37 presents a central annular recess 47 for receiving a steady supply of pressure water as through supply connection or passage 48, the recess 47 therefore constituting a stationary pressure supply chamber from which pressure water can be directed alternately to respective hydraulic operating chambers 18 and 21. To the left of recess or pressure chamber 47 there is provided an annular recess 49 communicating through two-way passage 22 with the hydraulic operating chamber 18, while to the right of pressure supply chamber 47 there is provided an annular recess 50 similar to recess 49 although communicating with the hydraulic operating chamber 21 by way of two-way passage 23. Both recesses 49 and 50 constitute transfer chambers in that through them hydraulic operating water passes to and from respective hydraulic operating chambers 18 and 21.

Furthermore, to the left of transfer chamber 49 at the end of the valve housing 37 there is provided a recess 51, constituting a discharge chamber for spent hydraulic operating water released from operating chamber 18 which released spent water must pass through discharge chamber 51 in order to reach a discharge passage 52 leading from the valve housing 37. Correspondingly, at the opposite end of the valve housing 37 there is provided a recess 53 constituting a discharge chamber for spent hydraulic operating water released from operating chamber 21 and dischargeable from the chamber 53 through a discharge passage 54 leading therefrom.

The sleeve member 41 has sets of port openings through which the various interior recesses or stationary chambers 47, 49, 50, 51, 53 of the valve housing may communicate with the interior of the sleeve member 41, these sets of port openings being so arranged that with the reciprocation of the spool member 42 they will control and direct the passage of hydraulic operating water to and from the hydraulic operating chambers 18 and 21 in a manner whereby there is effected the desired reciprocation of the diaphragms 16 and 19 in unison with the reciprocation of the sleeve member 41 and substantially in tune with the reciprocation of the spool member 42.

Such an arrangement of port openings comprise one or a set of port openings 55 communicating with the stationary pressure chamber 47 during all phases of reciprocation of the sleeve member 41; one or a set of port openings 56 associated with one or a set of port openings 57 spaced to the left therefrom, both openings 56 and 57 communicating with the stationary transfer chamber 49 during all phases of reciprocation of the sleeve member 41; and finally one or a set of port openings 58 associated with one or a set of port openings 59 spaced outwardly therefrom, both sets of openings 58 and 59 communicating with the stationary transfer chamber 50 during all phases of reciprocation of the sleeve member 41. The right-hand end of the sleeve member 41 is closed partially by virtue of its connection with the stem portion 45 providing for a set of one-way transfer passages 45^a for releasing therethrough spent hydraulic discharge water from the interior of the sleeve into the discharge chamber 53 and thence into the discharge passage 54.

The spool member 42 comprises a spool head 60 of the length (l) having a sliding fit within

the sleeve member 41, and formed with sliding cylindrical portions for controlling and directing the passage of hydraulic operating water through the respective port openings of the sleeve member 41 incident to the reciprocation of the spool member 42 relative to the movement of the sleeve member 41. That is to say, the spool head 60 is formed at its outer or right-hand end with a wide port closure portion 61 substantially defined by a cylindrical outer contour of the height h_1 and provided with horizontal relief passages 62. A similar port closure portion 63 is formed at the opposite end of the spool head, which closure portion has horizontal relief passages 64. Spaced inwardly from the port closure portion 63 is a narrow and solid flow-controlling and directing portion 65 resembling a circular rib portion defined by an outer cylindrical contour of the height h_2 , so that the closure portion 63 and the rib portion 65 form between them an annular narrow reciprocatable transfer chamber 66 of the width w_1 . A similar flow controlling and directing rib portion 67 is provided symmetrically with respect to the rib portion 65, so that there is formed between closure portion 61 and rib portion 67 a narrow reciprocatable transfer chamber 68 of a width w_1 equal to that of the other narrow reciprocatable transfer chamber 66. Thus, there is formed between the rib portions 65 and 67 a wide reciprocatable pressure supply chamber 69 which communicates at all times through port openings 55 with the stationary pressure supply chamber 47.

The pressure supply section S of the pump unit comprises a centrifugal servo-pump 70 having its pressure end 70^a connected to the pressure supply passage 48 leading into the valve housing 37 of valve unit V, and having its suction end 70^b connected as by a header 71 to both spent water discharge passages 52 and 54 leading from respective ends of the housing 37 of valve unit V. A reservoir or expansion chamber 72 is also connected to the suction end of the servo-pump by way of header 71.

The servo-drive mechanism D is represented in Figures 1 and 2 merely by a driven eccentric member 73 which through a slide block 74 engaging a vertical guide member 75 reciprocates the spool member 42.

Figures 1 and 2 illustrate the operation of the pumping cycle as effected by the reciprocatory pilot movement of the driven valve spool member 42. That is to say, Figure 1 shows the condition under which the diaphragm pump performs the one stroke of the pumping cycle, namely in the direction of arrows A, whereas Figure 2 shows the condition under which the diaphragm pump performs the opposite stroke of the pumping cycle, namely in the direction of arrows A₁. It should be noted that during both pumping strokes, in other words that throughout the entire pumping cycle, the full operating water pressure is present and available in the reciprocatable pressure supply chamber 69 because of the constant communication of that chamber through port openings 55 with the stationary pressure supply chamber 47 and thus with the pressure end of the centrifugal servo-pump 70.

According to Fig. 1, if the eccentric member 73 rotates in the direction of arrow B moving the spool member 42 from dead center point O₁ towards dead center point O₂, its movement relative to the sleeve member 41 is such that the port openings 58 in the sleeve member become partly and sufficiently uncovered by the move-

ment of the spool member 42 leading the movement of the sleeve member 41, thereby admitting pressure water in the direction of arrows C from the reciprocatable pressure supply chamber 69 through port openings 58, stationary transfer chamber 56, and passage 23 into the hydraulic operating chamber 21, although the associated port openings 59 remain closed during this stroke.

At the same time and by the same token (during the Figure 1 leftward stroke of the pump) the port openings 56 as well as the openings 57 are uncovered to the same extent that the openings 58 are uncovered, yet in the opposite sense whereby spent hydraulic operating water is released in the direction of arrows E from the operating chamber 18 through passage 22, transfer chamber 49, then simultaneously through both sets of port openings 56 and 57, through the reciprocatable transfer chamber 56 and the transfer passage 64 into the stationary discharge chamber 51 whence the spent operating water leaves the valve housing by way of the discharge passage 52 leading to the suction end of the servo-pump 70 by way of header 71. Thus, the spool member 42 in moving from dead center point O₁ to dead center point O₂ slightly leads the movement of the sleeve member 41 while effecting the pump stroke in the leftward direction of arrow A, thereby effecting the delivery of pumped slurry from pump chamber 20 through check valve 31, at the same time drawing slurry through the check valve 28 into the pumping chamber 17.

Considering the Figure 2 operating condition of the pump unit, if the eccentric member 73 continues rotating so that the movement of the spool member 42 is reversed and therefore moves from dead center point O₂ back to dead center point O₁ in the direction of arrows F, this will reverse the flows through respective sets of port openings in the sleeve member, again as the movement of the spool member 42 slightly leads the movement of the sleeve member 41 in the direction of arrows F, while effecting the pump stroke in the rightward direction of arrows A₁.

That is to say, the Figure 2 rightward stroke of the diaphragm pump is effected by pressure water obtained from the reciprocatable supply chamber 69 and being admitted through port openings 56 being partly uncovered, and through the stationary transfer chamber 49, and through the passage 22 into the hydraulic operating chamber 18, while the associated port openings 57 remain closed. At the same time and by the same token, the port openings 53 and 59 become uncovered to the same extent as the openings 58 are uncovered although in the opposite sense and in such a way that spent operating water is released from the hydraulic operating chamber 21 by way of the passage 23, stationary transfer chamber 50, port openings 58 and 59, reciprocatable transfer chamber 68, transfer and relief passages 62 and 45^a, into the discharge chamber 53, and hence by way of discharge connection 54 and header 71 to the suction end 70^a of servo-pump 70.

In this way, Figures 1 and 2 illustrate the pumping cycle whereby the diaphragms 16 and 19 are actuated and reciprocated against the pump delivery pressure and in tune with those reciprocations which are controllably imparted to the spool member 42. The pump unit is started by starting the servo-pump 70 so as to provide and supply a steady available hydraulic

operating pressure to the control valve unit V, and also starting the reciprocation of the spool member 42 by starting the servo-drive means or -unit D. The position of the spool member 42 relative to the sleeve member 41 controls and directs the admission of pressure water to, as well as the release of spent operating water from the respective hydraulic operating chambers 18 and 21, thereby actuating and reciprocating the diaphragms 16 and 19 in unison with the sleeve member 41. In this way, while the pump unit operates against a certain delivery head or back pressure, the spool member 42 will lead the movement of the sleeve member 41 by a distance corresponding to the uncovered area of the port openings in the sleeve member, thereby automatically supplying to the hydraulic operating chambers 18 and 21 the amount of pumping pressure needed for maintaining the desired output or pumping rate of the pump.

In the event that for any reason the delivery head or load of the pump increases, there will occur coincidental with such increase a momentary retardation in the movement of the diaphragms 16 and 19 and therefore also in the movement of the sleeve member 41, the amount of such retardation or relative movement between the spool member and the sleeve member at that time being only so much as to allow just enough additional lead for the spool member 42 to increase the through-flow area or the pressure supply port openings sufficiently to satisfy the additional pressure needs of the pump, with the pump then automatically accepting and maintaining this new setting as well as maintaining its discharge rate.

Similarly, in the event that the delivery head or load of the pump decreases, there will occur coincidental with such decrease a momentary acceleration in the movement of the diaphragms 16 and 19 and therefore also in the movement of the sleeve member 41, the amount of such acceleration or relative movement between the spool member and the sleeve member at that time being only so much as to reduce the lead of the spool member 42 to decrease or throttle down the through-flow area of the pressure supply port openings sufficiently to meet the reduced pressure needs of the pump, with the pump then maintaining this new setting as well as maintaining its discharge rate.

In the case of blockage of any one of the two or of both discharge valves or discharge passages of the pumping chambers 18 and 21, in spite of the absence of special relief devices, no damage will occur to any part of the pump unit since nothing would happen except that the delivery of the diaphragm pump would stop while the centrifugal servo-pump 70 would continue running and merely produce its predetermined maximum pressure without actually delivering. Any loss of hydraulic operating water from the pump unit that might occur in the course of the normal operation of the pump unit or in the event of the aforementioned blockages or stoppages, is automatically made up by the servo-pump 70 drawing make-up water as needed from the reservoir or expansion chamber 72 communicating with the suction end of that pump.

With respect to the controllability of the discharge rate of the pump unit it will be understood from the foregoing that one only needs to speed up the servo-drive mechanism D in order to thereby proportionately increase the delivery rate of the pumping unit, or else to slow down

the servo-drive D in order to thereby proportionately decrease the delivery rate of the pumping unit, inasmuch as each stroke of the spool member 42 produces and corresponds to an active pumping stroke of the diaphragm pump. Another mode of controlling or varying the delivery rate of the pump unit is by varying the length of the stroke of the spool member 42 as by varying the effective eccentricity of the eccentric member 73.

Figures 3 and 4 present the pumping unit still diagrammatically, yet in some respects more fully structurally evolved than the diagrammatic embodiments shown in Figures 1 and 2. However, the operating condition and position of parts in Figure 3 correspond to those in Figure 1, whereas Figure 4 in this respect corresponds to Figure 2.

As for Figure 3, again the main component portion or sections of the pump unit are identifiable as such and boxed-in by dot-and-dash outlines so that the diaphragm pump section may be designated as P', the control valve section V', the servo-drive section as D', and the pressure water supply section as S'.

The significance of these component sections P', V', D' and S' as well as the operation of the pump unit having been presented in connection with the foregoing description of the diagrammatic Figures 1 and 2, it should now suffice to point out and describe substantially only the features of structural evolution of the pump unit whereby Figures 3 and 4 differ from Figures 1 and 2.

Diaphragms 13 and 14 provided within a housing 75 define a pair of pumping chambers 76 and 77 as well as a pair of hydraulic operating chambers 78 and 79. The pumping chambers 76 and 77 have a two-way passage 80 and 81 respectively, which lead to respective valve heads 82 and 83. The valve head 82 serving the pumping chamber 76 has an inlet ball check valve 84 and an outlet ball check valve 85, while the valve head 83 serving the pumping chamber 77 has an inlet ball check valve 86 and an outlet ball check valve 87. The hydraulic operating chamber 78 has a passage 88 connecting it with the control valve unit V', while the hydraulic operating chamber 79 has a passage 89 connecting it with the control valve unit V'. All these parts of the diaphragm pump section P' of Figure 3 are readily identified with corresponding parts in pump section P of Figure 1.

The control valve section V' comprises a stationary housing 90 connected to the pump housing 75 through the aforementioned passages 88 and 89, a sleeve member 91 having axially sliding fit in the valve housing 90, and a spool member 92 which in turn has axially sliding fit within the sleeve member 91. The sleeve member 91 has various sets of port openings which are here merely designated by the collective letter L although these port openings correspond functionally to openings 56, 56, 57, 58, 59 in Figure 1 and they bear the above described operational relationship with respect to passages 88 and 89 and the hydraulic operating chambers 78 and 79 as well as with respect to the spool member 92 which controls and directs the flow of pressure water and of operating water through these port openings such function of the port openings having been fully described above in the operation of the Figure 1 schematic embodiment of the pump unit. The spool member 92 is adapted to be reciprocated as by mechanism represented by servo-drive section D' indicated as identical

to corresponding section S of Figure 1. However, as an evolutional feature, an interconnection 93 is provided between the spent water discharging ends of the valve housing 90 and structurally more closely integrated with the valve housing which interconnection corresponds more or less to the header 71 of Figure 1. Therefore, a centrifugal servo-pump 84 (corresponding to servo-pump 70 of Figure 1) is shown to have a pressure connection 95 within the intermediate portion of the valve housing 90 as well as a suction connection 95^a with one end of the valve housing 90, an expansion chamber or reservoir 96 being connected with the suction connection 95^a.

Another evolutional feature of Figure 3 over Figure 1 lies in the mechanism for kinematically coupling the movement of the diaphragms 73 and 74 with that of the above sleeve member 91 so that the diaphragms and sleeve member will move in unison. Such mechanism according to Figure 3 comprises a pair of rocker shafts 97 and 98 extending within and transversely of the horizontal axis of the pump housing 75. That is to say, the rocker shaft 97 extending within operating chamber 78 has fixed thereon a first actuator arm 99 operatively connected as at 99^a to a stem 100 which extends outwardly and horizontally from the diaphragm 73, while the rocker shaft 98 has a similar first actuator arm 101 operatively connected as at 101^a to a stem 102 extending horizontally and outwardly from the diaphragm 74, the first actuator arms 99 and 101 being of equal length and parallel to each other. While both rocker shafts 97 and 98 are journaled in the walls of respective hydraulic operating chambers 78 and 79, each shaft has one end extending through and beyond the wall of the pump housing and in water-sealed relationship therewith, each of these rocker shafts thus presenting an outwardly exposed extension or end portion at the same side of the pump; whereas such exposed end portions of the rocker shafts are not visible directly in Figures 3 and 4, there is to be noted that each of them has fixed thereon a second actuator arm 103 and 104 respectively indicated in dot-and-dash lines, which pair of second actuator arms are parallel to and coextensive with as well as of the same length as the pair of first actuator arms 99 and 101. Furthermore, the second actuator arms 103 and 104 are operationally interconnected at their outer ends by means of a link rod 105 indicated by dot-and-dash lines. Moreover, the one of the second actuator arms, namely, arm 104 has a vertical extension arm 106 connected as at 107 operatively with the sleeve member 91, whereby the sleeve member is adapted to move in unison with the diaphragms 73 and 74.

Further structural evolution of the Figure 3 and 4 pump unit is shown in the perspective view of the pump unit in Figure 5 where a diaphragm pump section (corresponding to the section P' of Figure 3) is identifiable by a bracket with the designation P'', a control valve section (corresponding to section V' of Figure 3) is identifiable by a bracket with the designation V'', a servo-drive section (corresponding to the section D' of Figure 3) identifiable by a bracket with the designation D'', and a pressure supply section (corresponding to the section S' of Figure 3) identifiable by a bracket bearing the designation S''.

In the Figure 5 perspective view of the pump unit the diaphragm pump section P'' comprises a horizontally extending pump housing 108 shown with a front wall portion broken away and having

vertical closure end plates 109 and 110. The housing 108 because of a central vertical transverse partition wall 110^a comprises a pair of pumping sections 111 and 112 (corresponding to pumping sections 14 and 15 in Figure 1 or to pumping sections 14' and 15' in Figure 3). The pumping section 111 is divided by a diaphragm 113 into a hydraulic operating chamber 114 constituting the left-hand portion of the pump housing 108, and a slurry pumping chamber 115 proper constituting an intermediate portion of pump-housing 108. Similarly, the pumping section 112 is disposed symmetrically with respect to pumping section 111, the section 112 being divided by a diaphragm 116 into hydraulic operating chamber 117 constituting the right-hand end portion of the pump housing 108 and a slurry pumping chamber 118 proper forming an intermediate portion of that housing.

The diaphragms 113 and 116 are adapted to reciprocate in unison inasmuch as they are kinematically coupled by mechanism which comprises a pair of rocker shafts 119 and 120 which extend transversely of the horizontal axis of the pump housing 108 and which are journaled in the upper portion of that housing. The rocker shaft 119 extending within hydraulic operating chamber 114 has fixed thereon a first actuator arm 121 extending downwardly within that chamber and into operative connection as at 122 with a stem 123 extending horizontally outwardly from diaphragm 113. Similarly, the other rocker shaft 120 extending within the operating chamber 117 has fixed thereon a first actuator arm 124 extending downwardly within the operating chamber 117 and into operative connection as at 125 with a stem 126 which extends horizontally outwardly from diaphragm 116. The rocker shafts 119 and 120 each have an end portion 127 and 128 respectively extending through and beyond and being outwardly exposed from the wall of pump housing 108. The exposed end portion 127 of rocker shaft 119 has fixed thereon a second actuator arm 129 coextensive with and parallel to as well as of the same length as the associated first actuator arm 121 on that shaft. Similarly, the exposed end portion 128 of rocker shaft 120 has fixed thereon a second actuator arm 130 partly broken away which arm 130 is coextensive with and parallel to as well as of the same length as the associated first actuator arm 124 on that shaft. A link rod 131 partly broken away interconnects the lower ends of the second outer arms 129 and 130 so that thereby the diaphragms 113 and 116 are kinematically coupled to move in unison with one another. An extension arm 132 extends upwardly from the outer actuating arm 130 and into operative connection as at 133 with a valve sleeve member here merely indicated by its outer end or stem portion 134 for reciprocating the sleeve member within the control valve unit V'' in unison with the reciprocations of the diaphragms 113 and 116 (it being noted that the sleeve member or stem 134 is functionally similar and corresponds to the valve sleeve member 91 in Figure 3 or else to valve sleeve member 41 in Figure 1).

The control valve unit V'' is mounted upon and disposed substantially atop the pump housing 108 although placed somewhat towards one side thereof, namely the side adjoining the pressure supply unit S'', the disposition being such that the horizontal longitudinal axis of the sleeve unit V'' is parallel to the horizontal longitudinal axis of the valve housing 108. The con-

tral valve unit V'' which is here shown only by the outward appearance of a valve housing 134^a has at the bottom a pair of connections 135 and 136 each of which represents a two-way duct between the bottom portion of the valve housing and the top portion of respective associated hydraulic operating chambers 114 and 117, it being noted that these ducts 135 and 136 correspond functionally to passages 88 and 89 in Figures 3 and 4 or to passages 22 and 23 in Figures 1 and 2. A flow connection 137 (shown partly in full and partly in dot-and-dash lines) between the valve housing 134^a and the pressure supply section S'' represents a pressure water supply connection (which corresponds functionally to the passage 95 in Figure 3 or to passage 43 in Figure 1), the flow connection 137 connecting with the pressure end 138 of centrifugal servo-pump 140, such connections being indicated by a pair of pipe flanges F₁. A flow connection 141 (indicated partly in full and partly in dot-and-dash lines) extends between the valve housing 134^a and the suction or intake end 142 of servo-pump 140, such connection being indicated by a pair of pipe flanges F₂. A motor M is indicated for driving the servo-pump 140. A valve spool member operating within the valve unit V'' (which corresponds to spool member 92 in Figures 3 and 4) is here indicated only by its stem portion 143.

A servo-drive section D'' is here shown to be more fully implemented than in the previous Figures 1 and 3, and is shown to include not only an eccentric member 144, a slide member 145 and a vertical guide portion 146 for reciprocating the spool member 143, but also a self-contained gear motor unit 146^a for rotating the eccentric member 144 at a controllable rate of speed. That is to say, the gear motor unit 146^a comprises speed regulating means indicated by a speed control lever 147 whereby to vary the rate of reciprocation of the spool member 143 and thereby to vary the rate of reciprocation of the diaphragms 113 and 116 and hence varying the rate of delivery of the pump unit.

Slurry enters as well as leaves the pumping chambers 115 and 118 by way of a pair of two-way flow connections 148 and 149 shown partly in full and partly in dot-and-dash lines (which connections correspond to passages 80 and 81 in Figures 3 and 4). The connection 148 extends from the pump housing 108, namely from the opening 150 therein to a valve head H₁ (which corresponds to valve head 82 in Figures 3 and 4), the valve head H₁ comprising an inlet check valve indicated at 151 and an outlet check valve indicated at 152, whereby with the reciprocations of the diaphragm member 113 slurry is drawn in the direction of arrow R₁ through inlet check valve 151, connection 148, and opening 150 into the pumping chamber, and thereafter the slurry is expelled from that pumping chamber through opening 150, connection 148, and outlet check valve 152 as in the direction of arrows R₂. A reservoir or expansion chamber 153 is shown to communicate with the discharge side of the outlet check valve 152. Similarly, the connection 149 extends from the pump housing 108 as from the opening 154 at the bottom thereof to a valve head indicated by a bracket bearing the designation H₂ (corresponding to valve head 83 in Figures 3 and 4), the valve head H₂ comprising an inlet check valve indicated at 155 and an outlet check valve indicated at 156, so that with the reciprocations of the diaphragm member 116 slurry is drawn in the direction of arrows R₃ through inlet

check valve 155, flow connection 149, and opening 154 into the pumping chamber 118, and thereafter the slurry is expelled from pumping chamber 118 through opening 154, flow connection 149, and outlet check valve 156 in the direction of arrows R₄. A reservoir or expansion chamber 157 is shown to communicate with the discharge side of the outlet check valve 156.

Another reservoir or expansion chamber 158 is shown to be mounted upon and to rise from the top of the valve housing 134^a, which reservoir 158 corresponds functionally to the reservoir 96 in Figures 3 and 4 or to the reservoir 72 in Figures 1 and 2, although a connection such as the header 71 in Figure 1 for interconnecting the discharge valve chambers 51 and 53 is not visible in the Figure 5 embodiment inasmuch as in that embodiment such a connection is in effect provided not exteriorly but interiorly of the valve housing (more fully to be described below) in a manner whereby it connects the spent-water discharge valve chambers within the valve housing with each other as well as with the reservoir 158 and also with the intake 141 of the servo-pump 140, all as indicated functionally in the more diaphragmatic embodiments of Figures 1 and 3, and more fully described in connection with the Figures 6 to 18 embodiment.

Further structural development of the pump unit according to this invention over what has been described in the evolution from Figures 1 to 5 will now be described in conjunction with the embodiment shown in Figures 6 to 18.

Here the structural build-up is such that a diaphragm pump housing 159 and a motor driven servo-pump unit 160 have a common base plate or base structure 161, whereas the other accessories of the diaphragm pump housing, namely slurry handling valve heads 162 and 163 together with their respective expansion chambers 164 and 165 as well as a control valve unit 166 together with its expansion chamber 167 and its own servo-drive unit 167^a are all carried by and mounted atop the diaphragm pump housing 159.

The basic body portion of the pump housing 159 (see Fig. 9) resembles that shown in Figure 5 in that a central transverse partition wall 168 divides the pump housing into a pair of pump sections 169 and 170, each of which sections in turn is subdivided by a respective pump diaphragm into a hydraulic operating chamber and a slurry pumping chamber. That is to say, a diaphragm 171 divides the pumping section 169 into a hydraulic operating chamber 172 and a slurry pumping chamber 173, whereas diaphragm 174 divides the pumping section 170 into a hydraulic operating chamber 175 and a slurry pumping chamber 176. The outer ends of the hydraulic operating chambers 172 and 175 are represented by removable end plates or cover plates 177 and 178 respectively.

Mechanism is provided for kinematically coupling the diaphragms 171 and 174 with each other so they will reciprocate in unison, which mechanism is quite similar in arrangement and effect to that shown in the Figure 5 embodiment. That is to say, there are provided a pair of rocker shafts 179 and 180 extending transversely of the horizontal longitudinal axis of the pump housing 159 and journaled in the top portion thereof and in water-sealed relationship therewith. The rocker shaft 179 extending within the hydraulic operating chamber 172 has fixed thereon and extending downwardly therefrom a first actuator arm 181 operatively connected as at 182 with the

outer end of a stem 183 extending horizontally and outwardly from the diaphragm 171 with the hydraulic operating chamber 172. Similarly, the rocker shaft 180 extending within the hydraulic operating chamber 175 has fixed thereon and extending downwardly therefrom a first actuator arm 184 having operative connection as at 185 with a stem 186 extending horizontally and outwardly from the diaphragm 174 within the hydraulic operating chamber 175. The rocker shafts 179 and 180 each have an exposed end portion extending through and outwardly beyond the wall of the pump housing 159 at one side thereof (corresponding to similar exposed end portions 127 and 128 of rocker shafts 119 and 120 in Fig. 5). The exposed end portion (not visible) of rocker shaft 179 has fixed thereto a second actuator arm 187 which is coextensive with and parallel to as well as of the same length as the associated first actuator arm 184. Similarly, the exposed end portion of rocker shaft 180 has fixed thereto a second actuator arm 188 which is coextensive with and parallel to as well as of the same length as the associated first actuator arm 184. The lower ends of this pair of second or outer actuator arms 187 and 188 are interconnected by a link rod L₀ whereby the diaphragms 171 and 174 are kinematically coupled so as to reciprocate in unison with each other. One of the second or outer actuator arms, namely the actuator arm 188 has an upward extension arm 188^a the upper end of which has operative connection as at 188^b with the control valve unit 166.

The pump housing 159 is in the nature of a casting generally similar to housing 108 shown in Figure 5 although differing therefrom by having as integral parts of the casting a pair of ducts 186' and 187' for carrying operating water to and from the hydraulic operating chambers 172 and 175. The ducts 186' and 187' form openings 186^a and 187^a in the wall of the pump housing at the top of respective hydraulic operating chambers 172 and 175, whereas outwardly and upwardly these ducts terminate in a common horizontal rectangular flange 190 (note also the detail plan view thereof in Figure 11) where the ducts form duct openings 190^a and 190^b. Upon this horizontal flange 190 rests and is fastened as by means of bolts 190^c the housing 166^a of the control valve unit 166 the valve housing having bottom openings 191 and 192 registering with the openings 190^a and 190^b respectively of ducts 186' and 187'. Functionally these ducts 186' and 187' correspond to connections 135 and 136 in Figure 5 or else to passages 88 and 89 in Figures 3 and 4.

The pump housing or casting 159 furthermore comprises as an integral part thereof a pair of ducts 193 and 194 (indicated in dotted lines in Fig. 9) connecting the respective slurry pumping chambers 173 and 176 with valve heads 162 and 163 respectively. The inner ends of the slurry ducts 193 and 194 are defined by duct openings 195 and 196 in the wall of pump housing 159 at the bottom of respective slurry pumping chambers 173 and 176. The outer ends of the slurry ducts 193 and 194 are defined by duct openings 195^a and 196^a formed in a rectangular horizontal flange 197 (note detail showing in Fig. 11) which is coplanar with flange 190. The slurry duct 194 connects with an outlet or discharge ball check valve 198 which has communication with the expansion chamber 165 and has an outlet 198^a for discharging pumped slurry

75

in the direction of arrow R₅. The duct 194 has a branch connection 199 provided with an inlet ball check valve 200 for delivering slurry into the pumping chamber 176 as in the direction of arrow R₆. Thus, the check valves 198 and 200 of valve head 163 correspond functionally to check valves 156 and 155 of valve head H₂ in Figure 5. Similarly, the other slurry duct 193 connects to the outlet and inlet check valves of valve head 162 which functionally corresponds to check valves 151 and 152 of Figure 5. The inner ends of the slurry carrying ducts 193 and 194 are defined at their inner ends by the aforementioned duct openings 195 and 196 (see Fig. 9) whence these ducts rise vertically approximately for a length l₁ then to curve away from each other symmetrically each by way of an S-shaped length l₂, the upper ends of the ducts 193 and 194 being defined by the aforementioned duct openings 195^a and 196^a. The two slurry discharge check valves 198 and 198^a are structurally consolidated in a single casting having a flange 201 constituting the mate to flange 197 and fastened thereto as by bolts indicated at 202 in Figure 6 and also indicated by bolt holes 202^a in Figure 10 as well as by threaded holes 202^b in Figure 11. The expansion chambers 164 and 165 are fastened upon the respective outlet ball check valves 198 and 198^a as by swingable bolts 203 and the bottom openings of these check valves register with the duct openings 195^a and 196^a in the companion flange 197. Functionally the slurry ducts 193 and 194 correspond to connections 148 and 149 in Figure 5.

The control valve unit 166 of which a longitudinal vertical section appears in Figure 9 is comparable as to structural disposition with the control valve unit V'' in Figure 5 or else with respect to its main operating component members comparable to the valve unit V' in Figure 3 which in turn is functionally similar to valve unit V in Figure 1. The valve unit 166 comprises the housing 166^a disposed in a manner resembling that of valve housing 134^a in Figure 5, the valve housing 166^a in fact being in the form of a casting the details of which are shown in Figures 15, 16, 17, 18. Various recesses and valve chambers formed internally of the valve housing 166^a may be functionally identified with those shown in Figures 1 and 2. That is to say, the valve housing 166^a has a pressure supply chamber 47^a (functionally corresponding to valve chamber 47 of Figure 1 or valve chamber 47' of Figure 3), a pair of hydraulic water transfer chambers 49^a and 50^a (corresponding to valve chambers 49 and 50 of Figure 1 or valve chambers 49' and 50' of Figure 3), and a pair of spent-water discharge chambers 51^a and 53^a (corresponding to valve chambers 51 and 53 of Figure 1 or valve chambers 51' and 53' of Figure 3). The pressure supply chamber in fact comprises a pair of such chambers (see also the developed internal view of the valve housing in Figure 14^a) interconnected by a channel V. The pressure supply chamber 47^a connects with the pressure end 203^a of servo-pump 160 through an elbow-shaped pressure duct portion 234 which extends from the outer side of the valve housing 166^a integral therewith, and comprises a horizontal leg 205 (see Figs. 6, 15, 16) and a vertical leg 206 (see Figs. 7 and 8) having a flange connection comprising flanges 207^a and 207^b with the pressure end 203^a of servo-pump 160. The spent-water discharge chambers 51^a and 53^a are interconnected by a duct 208 which is formed in the top

21

portion of the valve housing 166^a and which also communicates with the expansion chamber 167, a communicating passage or opening 208^a being shown in Figure 9 as well as in Figures 15, 16, 17, 18. One of the spent-water discharge valve chambers, namely the chamber 53'' communicates with the intake end 209 of servo-pump 160 through an elbow-shaped discharge duct portion 210 (see Figs. 6, 7, 15) which extends laterally from the valve housing 166^a cast integral therewith and, in fact, cast integral also with the aforementioned elbow-shaped pressure duct portion 204. The spent-water discharge duct portion 210 consists of a horizontal leg 211 (see Figs. 6, 12, 15) of shallow S-shape leading from the valve chamber 53'', and of a horizontal straight leg 212 (see Figs. 6, 8, 15) having a flange connection comprising flanges 213^a and 213^b with a conduit portion or U-shaped pipe 214 leading from the discharge duct portion 210 to the inlet end 209 of servo-pump 160 and connected thereto as by flange connection comprising flanges 214^a and 214^b.

A control valve unit 166 (see Fig. 9) functions and controls the operating cycle of the pump unit substantially in a manner already described in connection with the more diagrammatic embodiments of Figures 1 and 3; that is to say, the valve housing 166^a has axially slideable within it a valve sleeve member 215 (note also the large detail perspective view thereof in Fig. 14) which sleeve member 215 corresponds to sleeve 41 in Figure 1. The sleeve 215 has a stem portion 216 the outer end of which is operatively connected at 188^b with the upward extension arm 188^a, the stem portion 216 extending through the end of valve housing 166^a in water-sealed relationship therewith, namely by way of a stuffing box 217 provided in an end plate 218 of the valve housing.

The sleeve member 215 (see Figs. 9 and 14) comprises a horizontal cylindrical body portion 219 one end of which has fixed thereon a plug-like end portion 220 having flow transfer passages 221 (which correspond functionally to the transfer passages 45^a in Fig 1), the sleeve member 215 furthermore having its stem portion 216 extending axially outwardly therefrom. The cylindrical body portion 219 of the sleeve member has sets of port openings 222, 223, 224, 225 and 226 which functionally correspond to such sets of port openings as are shown at 55, 56, 57, 58, 59 in Figure 1. Within the sleeve member 215 there is axially slideable a valve spool member 227 (see Figs. 9 and 13) which functionally correspond to the spool member 42 in Figure 1. The spool member 227 has a spool head 228 of the length l', and has a stem portion 229 extending axially outwardly from the spool head through the end of the valve housing in water-sealed relationship therewith, namely by way of stuffing box 230 provided in an end plate 231 of the valve housing. At the end of the stem portion 229 of the spool member and rigidly connected therewith is provided a vertical guide portion 229^a upon which (see Fig. 9) there is slideable a block or cross head 229^b actuated by an eccentric 229^c which in turn is driven by the servo-drive unit 167^a to effect reciprocation of the spool member 227 at a controllable rate. The spool head 228 is formed at its outer or right-hand end with a wide port-closure portion 232 substantially defined by a cylindrical outer contour of a height h₁' and provided with horizontal relief passages 233. A similar port-closure portion 234 is formed at the opposite end of the spool head and is pro-

22

vided with horizontal relief passages 235. Spaced inwardly in a horizontal axial direction from the port-closure portion 232 is a relatively narrower solid flow controlling-and-directing portion or circular rib portion 236 defined by an outer cylindrical contour of the height h₂' having an inwardly cone-shaped transitional portion 237, so that the closure portion 232 and the rib portion 236 form between them an annular narrow transfer chamber 238 of the width w₁' functionally corresponding to the reciprocating transfer chamber 68 of Figure 1. A similar flow controlling-and-directing annular rib portion 239 having an inwardly cone-shaped transitional portion 240 is provided symmetrically with respect to the rib portion 236, so that there is thereby formed between closure portion 234 and rib portion 239 a relatively narrow annular transfer chamber 241 of the width w₁' equal to that of the other annular transfer chamber 238 and functionally corresponding to the reciprocating transfer chamber 66 of Figure 1. Thus, there is formed between the annular rib portions 236 and 239 a wide pressure supply chamber 242 of the width w₂' which functionally corresponds to the reciprocating chamber 69 of Figure 1.

Measured in axial direction the dimension of the spool member 227 are so related to the axially measured dimensions of the sleeve member 215, 30 namely with respect to the distances between respective sets of port openings and the width of these openings themselves, that with the reciprocation of the spool member 227 there is effected the controlled admission to and release from the 35 operating chambers 172 and 175 of operating water in unison with the slurry pumping cycle of the pumping unit.

The operation of this pumping cycle is furthermore illustrated (see Figs. 19, 20, 21, 22) by means 40 of the expedient of diagrammatically indicating the valve housing as well as the sleeve member both developed with the plane of the sleeve member shown superposed upon and in proper operating relationship to the plane of the valve housing. For the present purpose the showing of the spool member is omitted from this superposed arrangement of the parts, but the horizontal axis of the developed members is indicated as x—x in each of the Figures 19 and 22, that axis being indicative of the line of movement of the sleeve member relative to the valve housing. Figures 19 and 20 represent a valve-operating cycle by indicating the positions of the sleeve member corresponding to valve conditions represented in Figures 1 and 2 and Figures 3 and 4 respectively. Thus in Figures 19 and 20 the simplified structural interrelationship of these parts is in accordance with the representations of Figures 1 and 2, whereas Figures 21 and 22 represent a similar valve operating cycle although comprising certain structural refinements such as will be explained more clearly below by reference to the Figure 15 perspective detail view of the valve housing.

The phase of the valve operating cycle that is 65 represented in Figure 19 corresponds to the operating phase shown in Figure 1 where the diaphragm pump is just starting its leftward stroke in the direction of arrow A as a consequence of the spool member 42 starting to move in the opposite or rightward direction of arrow B; Figure 20 represents the position of the sleeve member relative to the valve housing corresponding to the operating phases shown in Figure 2. The extent of the movement of the sleeve member relative to the valve housing is designated by the 70

stroke length D_0 , one such length being the equivalent of one half of the valve operating cycle as well as the equivalent of one half of the slurry pumping cycle of the pump unit, in that the stroke of the sleeve member is in unison with the stroke of the diaphragm pump.

That is to say, in Figure 19 the developed interior of the valve housing is represented at 243 in full lines, whereas the sleeve member developed and superimposed thereon is represented by the dot-and-dash line showing of the port openings therein. Thus, the interior stationary recesses or valve chambers in the valve housing of Figure 1 appear in Figure 19 as parallel strips or zones extending transversely of the horizontal reference axis $x-x$, so that the valve chambers 47, 49, 50, 51, 53 of Figure 1 correspond functionally to transverse zones 244, 245, 246, 247, 248 respectively of Figure 19; the spent-water discharge passages 52 and 54 of Figure 1 leading from respective valve end chambers 51 and 53 of Figure 1 are indicated by openings 249 and 250 in the valve housing 243 of Figure 19; the passages 22 and 23 of Figure 1 are indicated by openings 251 and 252 respectively in Figure 19, while the pressure supply passage 48 of Figure 1 is indicated at 253 in Figure 19.

The port openings 55, 56, 57, 58, 59 of the Figure 1 sleeve member are represented in Figure 19 by the dot-and-dash line slot-like openings correspondingly designated as 254, 255, 256, 257, 258, which port openings are here shown substantially in their extreme left-hand position relative to the aforementioned stationary valve chambers or zones, the then flow-conditions and flow-directions within the valve unit being as shown and described above for Figure 1, but with due consideration to the functioning of the spool member 42 which at that time may be said to be about leaving its lefthand dead-center position to initiate a stroke of the valve operating cycle as well as the corresponding stroke of the slurry pumping cycle of the pump unit. In Figure 20 the dot-and-dash line slot-like port openings 254, 255, 256, 257, 258 representing the sleeve member are shown substantially in their extreme right-hand position relative to the stationary valve chambers or zones, the then flow-conditions and flow-directions within the valve unit being as shown and described above for Figure 2, but with due consideration to the functioning of the spool member 42 which at that time may be said to be about leaving its right-hand dead-center position, to initiate the return stroke of the valve operating cycle as well as the corresponding stroke of the slurry pumping cycle of the pump unit.

The Figure 21 embodiment differs from that of Figure 19 by structural refinements but not in function, the net result of the refinements being that the structural horizontal length of the valve housing is appreciably fore-shortened whereby the structural combination of the valve unit with the diaphragm pump proper and its accessories is facilitated and is rendered desirably compact. The valve housing is here designated by the numeral 242' whereas the port openings of the sleeve member are designated as 254', 255', 256', 257', 258' functionally corresponding to the port openings 254, 255, 256, 257, 258 of Figure 19. Foreshortening of the valve housing from a length L_1 to a length L_2 is herein accomplished without incurring undue restriction of needed flow passage area in the valve unit, as will presently appear. Referring to Figure 19, such fore-shortening of the valve housing is accomplished in effect

by reducing the aggregate length L_1' of zone 244, 245, 246 to the shorter aggregate length L_2' of corresponding zones 245' and 246' in Figure 21, namely by substituting a pair of pressure supply openings 259' and 260' instead of the single opening 253 of Figure 19, thus allowing the spent-water discharge openings 251 and 252 of Figure 19 to be moved closer together as is shown by the relative location of corresponding openings 251' and 252' in Figure 21; as well as by changing and rearranging the dividing ridges R_1 and R_2 which between them define the center zone 244 in Figure 19 in such a manner that a pair of square shaped ridge portions R_3 and R_4 are made to surround and frame in the pressure supply openings 259' and 260' respectively while rib-like ridge portions R_5 and R_6 interconnect the square-shaped ridge portions R_3 and R_4 in a direction transversely of the valve housing.

In Figure 22 which functionally corresponds to Figure 20 the dot-and-dash line port openings 254', 255', 256', 257', 258' representing the sleeve member are shown substantially in their extreme right-hand position relative to the stationary valve chambers or zones, the then flow-conditions and flow-directions within the valve unit being as shown and described above with respect to Figure 2 where the spool member 42 is just about leaving its right-hand dead-center position to execute its leftward stroke.

In Figure 23 all numerals concerning parts or portions of the spool valve are substantially the same as given in Figures 9, 13, 14, but with the addition of certain functionally important dimensional relationships and with emphasis upon certain bevelled configuration of the closure portions 234, 239, 236, 232 of the spool member 229.

That is to say, the left-hand outer closure portion 234 is formed with a conical bevel at each side, namely bevels 234^a and 234^b under a steep angle β ; while the right-hand outer closure portion 232 is similarly formed with bevels 232^a and 232^b also under steep angle β . The two intermediate closure portions 236 and 239 are formed at their inner sides with shallow bevels 237 and 240 respectively under angle α while their outer sides are formed with steep bevels 237^a and 239^a respectively under angle β .

The passages 223 and 224 are indicated each to be of a width m and to be spaced from each other a distance n ; the passages 225 and 226 also are of the width m and are spaced from each other a distance n . The functionally important distance between the left-hand edge of passage 224 and the left-hand edge of passage 223 is indicated by the dimension b which is also the distance between the respective right-hand edges of passages 224 and 223, which dimension b further repeats itself as between the respective left-hand edges E_1 and E_2 of closure portions 234 and 239.

Furthermore, in order that the spool valve may function properly, the effective width h_2' of closure portion 236 and 239 should be equal to the width m of the associated passages 223 and 225, whereas the effective width h_1' of the closure portions 233 and 234 is at least twice the width m of associated passages 224 and 226 respectively.

A further qualification of the spool valve as to its proper functioning lies in the fact that the axial motion of the spool member within the sleeve member is confined between a pair of end stops, namely on the one hand an abutment ring member 259 press-fitted into the sleeve member and presenting the inner abutment face 259^a, and

on the other hand the plug element 220 presenting an inner abutment face 220^a. The disposition of the abutment faces 259^a and 220^a is such that the closure portions 234 and 232 will be prevented from overrunning the passages 224 and 226.

The servo-drive unit 167^a (see Figs. 5, 6, 7, 9) is exemplified as by known variable speed drive unit of the type that has friction drive by way of tapered rollers operating on an internal traction ring, which unit has a maximum output torque at its output shaft, beyond which it will not operate. That is to say, the output shaft of this servo-drive unit could be stopped, for example, as by blockage of the pump without there resulting any damage to motion transmitting parts even while the motor may continue running. In other words, damage is precluded in case the movement of the valve sleeve member might become blocked as by blockage of the pump discharge. Subsequent to removal of such hypothetical blockage, the sleeve member would be free to resume its movement and the drive unit would then again drive the valve spool member the full length of its stroke. In this way, the pump if it should become blocked would automatically resume normal operation after removal of the blockage as the moving parts of the valve unit, namely the spool member and the sleeve member would then automatically get back into step with each other.

The object of the bevels α and β of the valve spool member 221 is to present as large a passageway as possible for the spent water passing from the hydraulic operating chambers of the pump while keeping the passageways for pressure water passing into the operating chambers as small as possible by comparison. This is in order to provide a pressure drop across the spent water passageway that is as small as possible, while by comparison rendering the pressure drop across the pressure water passageway as large as possible. In other words, the relative effects of the bevel angle α is to reduce the pressure drop, and that of bevel angle β to increase the pressure drop.

The significance of this refinement with respect to operation of the pump will appear more clearly as follows:

The movement of the valve spool member 221 in relation to the sleeve member 215 is such (see Figs. 1 and 2) that the pressure passageway or port begins to open at the same time that the two spent water passageways or ports are starting to open, and further movement of the valve spool member in the sleeve member uncovers exactly the same longitudinal fraction of width of the pressure port as it does of each of the two corresponding spent water ports in the sleeve member. If the valve spool member did not have such bevels as are indicated at α and β or if all the bevels were assumed to be of the same angle, the area of the spent water ports would be twice the area of the pressure water ports. At any rate, there is just as much water flowing through the pressure port as through the corresponding spent water ports, so that if the area of the spent water ports is twice that of the pressure port, then the pressure drop across the pressure port is four times the pressure drop across the spent water ports. This then answers the above requirement of having the pressure drop across the spent water port as small as possible in relation to the pressure drop across the pressure water port.

In order to increase this ratio of pressure drop

through the pressure port to the pressure drop through the spent water ports, the spool valve member is beveled as indicated by the angles α and β so that for a given movement of the spool valve member relative to the sleeve member, each of the spent water ports presents a relatively greater amount of port area than the corresponding pressure port.

The effect of this refinement is to enable the pressure and the suction end of the servo-pump to operate under conditions such that there is attained a maximum of stress relief for the pump diaphragms. For example, if no pressure drop were encountered through the spent water ports with the suction pressure of the servo-pump assumed to be the same as the suction in the slurry pumping chamber to pull in the slurry, then no pressure difference would appear between the two sides of each pump diaphragm and the diaphragm would thus be fully stress relieved.

I claim:

1. A double-acting stress-relieved diaphragm pump having a pump housing structure provided with a pair of diaphragms each of which is confined in said housing structure between a body of hydraulic operating water and a body of slurry being pumped, with partition means provided between said bodies of slurry, said housing structure thus providing a hydraulic operating chamber at one side and outwardly from each respective diaphragm and a slurry pumping chamber at the other side of and inwardly from each respective diaphragm, each slurry pumping chamber having an inlet check valve and an outlet check valve, each hydraulic operating chamber being adapted to have pressure operating water controllably fed thereto and released therefrom as spent operating water for alternately producing pressure and suction in the respective slurry pumping chambers, control means for so feeding and releasing the operating water with respect to the hydraulic operating chambers, comprising a spool type valve unit having a cylindrical valve housing provided with a pair of internal recesses constituting a pair of transfer chambers spaced from each other longitudinally of the valve housing, each such transfer chamber having a two-way conduit connecting it with a respective operating chamber, said valve housing also having a third recess constituting a pressure water supply chamber disposed intermediate said transfer chambers and having supply conduit means for receiving said pressure water, said valve housing further having at each end thereof a spent water discharge chamber each of which has a discharge conduit, said valve unit further comprising a valve sleeve member axially reciprocable in said valve housing and adapted to close said recesses except for port openings provided in the sleeve member, a supply port opening being provided for said supply valve chamber, and a pair of transfer port openings being provided for each of said transfer valve chambers, the openings of each such pair of transfer port openings being spaced from each other and from the other pair in the longitudinal direction of the sleeve member so that each pair of transfer port openings comprises an outwardly and an inwardly disposed opening with the inwardly disposed openings located between the outwardly disposed openings, a spool valve member axially slidable reciprocatably within said valve sleeve member and adapted when so reciprocating to establish a flow passage through the inwardly disposed transfer port opening of

the one of said pairs for pressure water to be admitted from and through the interior of the sleeve member and through the supply port opening to one hydraulic operating chamber while blanking the associated outwardly disposed transfer port opening and while unblanking the other pair of transfer port openings to establish flow passage therethrough for spent operating water from the other hydraulic operating chamber to the associated spent water discharge chamber, said spool member, vice versa, being adapted to establish flow passage through the inwardly disposed transfer opening of said second pair for pressure water to be admitted from and through the interior of the sleeve member and through the supply port opening to said other hydraulic operating chamber while blanking the associated outwardly disposed transfer port opening and while unblanking said one pair of transfer port openings to establish flow passage therethrough for spent operating water from said one hydraulic operating chamber to its associated spent water discharge chamber, said spool member comprising for each said pair of transfer port openings a correspondingly disposed pair of cylindrical closure portions one of which is outwardly disposed and has a transfer passage leading from the inner side to the outer side thereof and the other one of which closure portions is inwardly disposed so that the inwardly disposed closure portions are located between the outwardly disposed closure portions, each pair of closure portions having an effective spacing between them and from the other pair and each closure portion having a cylindrical length so coordinated to said spacings that the above defined flow passages between the respective hydraulic operating chambers and the pressure water supply chamber on the one hand and the spent water discharge chambers on the other hand are established incident to the reciprocation of the spool valve member; mechanical motion transmitting means operatively interconnecting said diaphragms and also effective between said diaphragms and said sleeve member whereby said diaphragms move in unison with each other as well as with said sleeve member; and servo-drive means operatively connected with said spool valve member for controllably reciprocating said spool member whereby said sleeve member and said diaphragms are adapted to correspondingly follow the controlling movements of the spool member.

2. A double-acting pump according to claim 1, in which the pressure water supply is provided by a centrifugal servo-pump, in which spent operating water returns from said water discharge chamber through said discharge conduits to the suction end of the pump, and in which pressure water from the discharge end of the pump passes through said supply conduit means to said pressure water supply chamber with the addition of an expansion chamber communicating with the suction end of the servo-pump.

3. A double-acting pump according to claim 1, in which the servo-drive means comprise a motorized reduction gear drive unit having adjustable control means for varying the speed of said reciprocating movement.

4. A double-acting pump according to claim 1, in which both slurry pumping chambers are disposed between and horizontally coextensive with said hydraulic operating chambers, the hydraulic operating chambers thus occupying respective end portions and the slurry pumping chambers

occupying the intermediate portion of said housing structure, and in which said mechanical motion transmitting means comprise a stem extending horizontally outwardly from each diaphragm, a horizontal rocker shaft provided for each said horizontal stem and extending within said housing structure transversely of the horizontal axis thereof, a downwardly extending arm within the housing fixed upon each shaft and rockable therewith, both rockable arms being parallel and downwardly coextensive each having its lower end pivotally connected to the outer end of a respective stem, both shafts having one end extending through and protruding beyond the housing wall in sealing relationship therewith, a second arm fixed upon the protruding end portion of each shaft, said second arms extending downwardly parallel to each other as well as parallel to the first-mentioned rocker arms, a link member interconnecting said second rocker arms whereby said diaphragms are adapted to move in unison and connecting means for operatively interconnecting one of said shafts with said sleeve member whereby the latter is adapted to move in unison with said diaphragm.

5. A double-acting pump according to claim 1, in which both slurry pumping chambers are disposed between and horizontally coextensive with said hydraulic operating chambers with the hydraulic operating chambers thus occupying the end portions housing whereas the pumping chambers occupy the intermediate portion of said housing structure; in which said valve housing is mounted substantially atop the housing structure with its longitudinal horizontal axis coextensive relative to that of the housing structure, and said sleeve member has a stem extending coaxially therewith through one end of the valve housing in sealed relationship therewith, and said spool member has a stem extending coaxially therewith through the other end of the valve housing in sealed relationship therewith; and in which said mechanical motion transmitting means comprise a stem extending horizontally outwardly from each diaphragm, a horizontal rocker shaft provided for each of said horizontal stems and extending within said housing transversely of the horizontal axis thereof, a downwardly extending actuator arm within the housing fixed upon each said shaft and rockable therewith, both rockable actuator arms being parallel to each other and each having its lower end pivotally connected to the outer end of a respective diaphragm stem, both shafts having one end extending through and protruding beyond the wall of the housing structure sealing relationship therewith, a second actuator arm fixed upon the protruding end portion of each shaft, both said second actuator arms extending downwardly parallel to each other as well as parallel to the first-mentioned rocker arms, a link member interconnecting said second rocker arms whereby said diaphragms are adapted to move in unison, and an auxiliary rocker arm extending upward from the protruding end portion of one of said shafts and into cooperative engagement with the stem of said sleeve member whereby the latter is adapted to move in unison with said diaphragm.

6. A double-acting pump according to claim 1, in which both slurry pumping chambers are disposed between and horizontally coextensive with said hydraulic operating chambers with the hydraulic operating chambers thus occupying the end portions and the slurry pumping chambers occupying the intermediate portion of said hous-

ing structure; in which said valve housing is mounted substantially atop the housing structure with its longitudinal horizontal axis coextensive relative to that of the housing structure, said sleeve member has a stem extending coaxially therewith through one end of the valve housing in sealed relationship therewith, and said spool member has a stem extending coaxially therewith through the other end of the valve housing in sealed relationship therewith; in which said mechanical motion transmitting means comprise a stem extending horizontally outwardly from each diaphragm, a horizontal rocker shaft provided for each of said horizontal stems and extending within said housing transversely of the horizontal axis thereof, a downwardly pointing actuator arm within the housing fixed upon each said shaft and rockable therewith, both rockable actuator arms being parallel to each other and each having its lower end operatively connected to the outer end of a respective diaphragm stem, both shafts having one end extending through and protruding beyond the wall of the housing structure in sealing relationship therewith, a second actuator arm fixed upon the protruding end portion of each shaft, said second arms extending downwardly parallel to each other as well as parallel to the first-mentioned rocker arms, a link member interconnecting said second actuator arms whereby said diaphragms are adapted to move in unison, and an auxiliary rocker arm extending upward from the protruding end portion of one of said shafts and into cooperative engagement with the stem of said sleeve member whereby the latter is adapted to move in unison with said diaphragm; and in which said servo-drive means comprise a motor gear unit producing eccentric motion at the output end and means for converting said eccentric motion into reciprocating movement of the spool member, and means embodied in said unit for adjusting the speed of said eccentric motion.

7. A double-acting pump according to claim 1, in which both slurry pumping chambers are disposed between and horizontally coextensive with said hydraulic operating chambers with the hydraulic operating chambers thus occupying the end portions and the slurry pumping chambers occupying the intermediate portion of said housing structure, in which said valve housing is mounted substantially atop the housing structure with its longitudinal horizontal axis coextensive relative to that of the pump housing, said sleeve member has a stem extending coaxially therewith through one end of the valve housing in sealed relationship therewith, and said spool member has a stem extending coaxially therewith through the other end of the valve housing in sealed relationship therewith; in which said mechanical motion transmitting means comprise a stem extending horizontally outwardly from each diaphragm, a horizontal rocker shaft provided for each of said horizontal stems and extending within said housing transversely of the horizontal axis thereof, a downwardly pointing actuator arm within the housing fixed upon each shaft and rockable therewith, both said rockable actuator arms being parallel to each other and each having its lower end operatively connected to the outer end of a respective diaphragm stem, both shafts having one end extending through and protruding beyond the wall of the housing structure in sealing relationship therewith, a second actuator arm fixed upon the protruding end portion of each shaft, both said second actuator

arms extending downwardly parallel to each other as well as parallel to the first-mentioned rocker arms, a link member interconnecting said second actuator arms whereby said diaphragms are adapted to move in unison, and an auxiliary rocker arm extending upward from the protruding end portion of one of said shafts and into cooperative engagement with the stem of said sleeve member whereby the latter is adapted to move in unison with said diaphragm; and in which said servo-drive means comprise a motor gear unit producing eccentric motion at the output and means for converting said eccentric motion into reciprocating movement of the spool member, and means for adjusting the length of stroke of the eccentric motion.

8. A pump according to claim 1, in which each of said inwardly disposed cylindrical closure portions of the spool member is formed with a relatively steep and short conical bevel portion at the outer end and with a relatively shallow and long bevel portion at the inner end.

9. A pump according to claim 1, in which each of said inwardly disposed cylindrical closure portions of the spool member is formed with a relatively steep and short conical bevel portion at the outer end and with a relatively shallow and long bevel portion at the inner end, and in which each of said outwardly disposed cylindrical closure portions is formed with a relatively steep and short conical bevel portion at its outer end and is substantially squared off at its inner end.

10. A double-acting stress-relieved diaphragm pump having a pump housing structure provided with a pair of diaphragms each of which is confined in said housing structure between a body of hydraulic operating water and a body of slurry being pumped, with partition means provided between said bodies of slurry, said housing structure thus providing a hydraulic operating chamber at one side and outwardly from each respective diaphragm and a slurry pumping chamber at the other side of and inwardly from each respective diaphragm, each slurry pumping chamber having an inlet check valve and an outlet check valve, each hydraulic operating chamber being adapted to have pressure operating water controllably fed thereto and released therefrom as spent operating water for alternately producing pressure and suction in the respective slurry pumping chambers, control means for so feeding and releasing the operating water with respect to the hydraulic operating chambers, comprising a spool type valve unit having a cylindrical valve housing provided with a pair of internal recesses constituting a pair of transfer chambers spaced from each other longitudinally of the valve housing, each such transfer chamber having a two-way conduit connecting it with a respective operating chamber, said valve housing also having a third recess constituting a pressure water supply chamber disposed intermediate said transfer chambers and having supply conduit means for receiving said pressure water, said valve housing further having at each end thereof a spent water discharge chamber each of which has a discharge conduit, said valve unit further comprising a valve sleeve member axially reciprocable in said valve housing and adapted to close said recesses except for port openings provided in the sleeve member, a supply port opening being provided for said supply valve chamber, and a transfer port opening being provided for each of said transfer valve chambers, a spool valve member axially slidably reciprocata-

31

bly within said valve member and adapted when so reciprocating by one stroke to establish a flow passage through the one transfer port opening for pressure water to be admitted from and through the interior of the sleeve member and through the supply port opening to one hydraulic operating chamber while establishing flow passage through the other transfer opening for spent operating water from the other hydraulic operating chamber to the associated spent water discharge chamber, said spool member by the opposite stroke being adapted to establish flow passage through said other transfer opening for pressure water to be admitted from and through the interior of the sleeve member and through the supply port opening to said other hydraulic operating chamber while establishing flow passage through said one transfer opening for spent operating water from said one hydraulic operating chamber to its associated spent water discharge chamber, said spool member comprising for each transfer port opening a cylindrical closure por-

tion having an effective cylindrical length and an effective spacing between them whereby the above defined flow passages between the respective hydraulic operating chambers and the pressure water supply chamber on the one hand and the spent water discharge chambers on the other hand are established incident to the reciprocation of the spool valve member; mechanical motion transmitting means operatively interconnecting said diaphragms and also effective between said diaphragms and said sleeve member whereby said diaphragms move in unison with each other as well as with said sleeve member; and servo-drive means operatively connected with said spool valve member for controllably reciprocating said spool member whereby said sleeve member and said diaphragms are adapted to correspondingly follow the controlling movements of the spool member.
